ENTRANCE HANDLE OR THE LIKE

Robert K. Unter, Rockford, Ill., assignor to Keystone Consolidated Industries, Inc., Peoria, Ill., a corporation of Delaware

Filed Jan. 2, 1969, Ser. No. 15,182

Term of patent 14 years

Int. Cl. D8—03

U.S. Cl. D8—166

FIG. 1.

FIG. 2.

FIG. 3.

FIG. 4

FIG. 5.

FIG. 6.

FIG. 1 is a front elevational view of an entrance handle or the like embodying my new design;

FIG. 2 is a side elevational view thereof;

FIG. 3 is a top plan view thereof;

FIG. 4 is a bottom plan view thereof;

FIG. 5 is a cross sectional view thereof taken on the line 5—5 of FIG. 1; and

FIG. 6 is a cross sectional view thereof taken on the line 6—6 of FIG. 1.

I claim:

The ornamental design for an entrance handle or the like, substantially as shown.
